ROTARY PERCUSSION DRILL ASSEMBLY

John B. Baker, Canton, Ohio, assignor to The Timken Roller Bearing Company, Canton, Ohio, a corporation of Ohio

Application July 12, 1947, Serial No. 760,643

7 Claims. (Cl. 287—126)

1

This invention relates to rotary percussion drills of the kind comprising a drill rod and a separate drill bit having an axial socket at the end remote from the cutting end adapted to receive one end of the drill rod. Drill rods and bits of this general type are usually provided with interengaging threads, clamps, keys or other special securing devices, which are expensive and difficult to produce and involve danger of slippage or separation of the parts.

The present invention is concerned with overcoming disadvantages, such as those above mentioned. Its principal object is to provide a strong and durable connection between the bit and drill rod which will prevent relative rotary movement and accidental disengagement thereof and which is simple to produce and which will eliminate separate fastening devices.

The invention consists principally in providing the circumferential wall of the drill rod receiving socket of the bit with one or more longitudinal slits having one side edge offset inwardly relative to the other side edge so as to provide a shearing edge adapted to bite into the peripheral surface of the portion of the drill rod in said socket and thus prevent relative rotary and endwise movement of said drill rod and bit. The invention also consists in the drill bit and in the method employed in producing the inwardly offset edge of the slit.

In the accompanying drawings, which form part of this specification and wherein like symbols refer to like parts wherever they occur,

Fig. 1 is a side elevational view of a rotary percussion drill embodying my invention,

Fig. 2 is a cross-sectional view on the line 2—2 in Fig. 1,

Fig. 3 is a central longitudinal sectional view on the line 3—3 in Fig. 2,

Fig. 4 is an end elevational view of the drill rod receiving end of the bit before the attachment thereof to the drill rod,

Fig. 5 is a central longitudinal sectional view of said bit on the line 5—5 in Fig. 4,

Figs. 6, 7, 8, 9 and 10 are views similar to Figs. 1, 2, 3, 4 and 5, respectively, showing a modified form of drill,

Figs. 11, 12, 13 and 14 are views similar to Figs. 4 and 9 illustrating four further modifications of the invention; and

Fig. 15 is a view similar to Fig. 5, showing another drill of slightly modified form.

In Figs. 1 to 5, my invention is shown embodied in a rotary percussion drill bit comprising a cylindrical drill rod A and a separate drill bit B.

2

The drill rod A has an axial passageway 1 therethrough for the cleansing fluid or liquid used during the drilling operation.

The separate drill bit B comprises a substantially cylindrical body having a cylindrical axial socket 2 in one end adapted to snugly receive one end of the drill rod A and an axial passageway 3 leading from the bottom of said socket to the other or cutting end of said bit for conveying thereto cleansing fluid received from the axial passageway 1 in the drill rod A. The drill bit B is shown provided with a conventional cruciform cutting end comprising cutting teeth 4 that are disposed radially of the axial passageway 3 of said bit and extend outwardly of the cylindrical body thereof where they are supported by the usual ribs or buttresses 5 that are spaced apart circumferentially of said body exteriorly thereof and taper toward and merge into said body near the socket end thereof.

According to the present invention, the circumferential wall of the drill rod receiving socket 2 of the bit B is provided with a series of circumferentially spaced radial slits 6 which extend downwardly parallel to the longitudinal axis of said bit between the exterior buttresses 5 from the mouth or open end of said socket and terminate short of the bottom thereof in wide circular lower end portions 7. Each slit 6 is preferably arranged with one edge at or closely adjacent to one of the two buttresses 5 between which said slit is located; and said edge of said slit is offset inwardly to form in the socket 2 a shearing edge 8 adapted to grip or bite into the peripheral surface of the socket engaging portion of the drill rod A and thereby prevent relative rotary movement of said drill bit and rod. The shearing edge 8 of each slit 6 sinks into the drill rod A above the lower end thereof and thus also serves to prevent the bit B from coming off said drill rod.

While mechanical pressure may be employed to force one edge of the slits 6 inwardly to form the shearing edges 8 and to press them into the peripheral surface of the socket engaging portion of the drill rod A, I have discovered that the inwardly offsetting of said edge of said slit may be brought about by heating the annular side wall of the socket 2 to a temperature approaching spring temper and corresponding hardness and then quenching the heat treated wall. This method of offsetting one edge of the slit is based upon the well known principle that a heavy ring section contracts more than a light ring section after heat treating and quenching. Thus, dur-

ing the quenching operation, the heavy section provided by the exterior buttress 5 along one edge of said slit 6 in the circumferential wall of the socket 2 of the bit B causes the thick buttressed section of said wall to shrink a greater amount than the thin section thereof along the other edge of said slit and move inwardly relative to said other edge to form the inwardly offset biting edge 8 which sinks into the socket engaging end of the drill rod A.

The modified drill construction shown in Figs. 6 to 10, inclusive, is similar to that shown in Figs. 1 to 5, inclusive, except that the socket 2^a of the bit B¹ and the socket engaging end of the drill rod A¹ are correspondingly tapered, as at 9, and the slits 6^a pass through the circumferential wall socket at oblique angles to the center of the said socket. That is, either side of the slits, since both sides of the slit are parallel, is contained in a plane which is directed at an oblique angle to a radially directed plane containing an edge of the slit. The resulting chordwise arrangement of the slits 6^a provides sharp acute angled cutting edges 8^a along the inwardly offset edges thereof, the oblique angle of said cutting edges serves to resist endwise separation of the drill rod and bit and the correspondingly tapered portions of the socket and the rod end therein compensate for the greater contraction of the circumferential wall of the socket at the bottom thereof where the wall is of thicker section due to the tapered buttresses of the bit.

The modified bit B² shown in Fig. 11 is similar to that shown in Figs. 1 to 5, inclusive, except that the slits 6^b of the modified bit are located midway between the buttresses. In this construction, mechanical pressure is employed to force one edge of each slit inwardly to form the shearing edge.

In the modified construction shown in Fig. 12, the drill rod receiving socket 2^c of the bit B³ is of hexagonal shape. The slits 6^c pass through the circumferential wall of the flat-sided socket 2^c at an oblique angle to the center thereof and are disposed parallel to the longitudinal axis thereof. The slits 6^c open into the socket 2^c through two diametrically flat side faces thereof midway of the width of said faces.

The modified construction shown in Fig. 13 is also provided with a hexagonal drill rod receiving socket 2^d and two diametrically opposed slits 6^d which extend through the wall at oblique angles. In this construction, however, the slits 6^d open into the flat-sided socket at two diametrically opposed corners thereof.

The modified bit shown in Fig. 14 has a four-sided socket 2^e with rounded corners and the slits 6^e open into said socket at the rounded corners thereof.

The drill bit shown in Fig. 15 is similar to that shown in Fig. 5, except that the slits 6^f are of uniform width from top to bottom, instead of having enlarged lower end portions. With this arrangement, the inwardly offset edge of the slit will draw in more at the bottom than at the top under heat treatment.

In each of the hereinbefore described drill constructions, the inwardly offset cutting or shearing edges of the longitudinal slits in the circumferential wall of the drill rod socket of the drill bit bite into and interlock with the peripheral surface of the portion of the drill rod in said socket and thus prevent relative rotary movement and endwise separation of said drill

rod and bit. In the construction shown in Fig. 11, one side of the slits is forced inwardly by mechanical pressure to form the shearing edges of the slits. In the other constructions, the inwardly offset cutting edge may be produced by mechanical pressure or by heating and quenching the circumferential wall of the socket so that the thick buttressed portion of the wall contracts to a greater extent than the thinner portion of said wall without the buttress. The circular lower end portions of the slits provide terminals for the slitting tool and facilitate heat treating, but these enlarged lower end portions may be omitted, as shown in Fig. 15. In heat treating the bit, the cutting edges of the slits are given a spring temper and are hard enough to bite into the softer metal of the drill rod. The oblique angle at which the slits extend through the circumferential wall of the socket provides sharp acute angled cutting edges along the inwardly displaced edges of the slits; and the oblique angle of said cutting edges relative to the longitudinal axis of the bit serves to prevent endwise separation of the bit and drill rod. The drill rod and socket may be of any desired shape; and one or more slits may be employed. The circumferential spacing, angle and number of the slits may also be varied as well as the number and arrangement of the cutting edges of the bit. While it is preferable to first offset the edges of the slits and then force the drill steel into the socket of the bit, the edges of the slits may be offset into gripping engagement with the drill rod after the latter is inserted in the socket of the bit.

What I claim is:

1. In a rotary percussion drill comprising a drill bit provided with an axial socket having a circumferential side wall with circumferentially spaced buttresses on the outer periphery thereof and a drill rod having a portion disposed in said socket, the improvement which consists in providing said wall between buttresses with longitudinal slits, one margin of each of which is offset inwardly into permanent interlocking engagement with the peripheral surface of the socket engaging portion of said rod.

2. The combination set forth in claim 1 wherein the inwardly offset margin of at least one of said slits terminates short of the bottom of said socket and the corresponding end of the rod therein.

3. The combination set forth in claim 1 wherein the inwardly offset margins of said slits have acute angled inner longitudinal cutting edges adapted to bite into the peripheral surface of said rod.

4. The combination set forth in claim 1 wherein said slits are each contained in a plane directed chordwise of said socket at an oblique angle to a radially directed plane containing an edge of the slits.

5. The combination set forth in claim 1 wherein said socket and the portion of the rod disposed therein have flat sides and the slits open into said socket substantially midway of the width of said sides.

6. The combination set forth in claim 1 wherein said socket and the portion of the rod disposed therein have flat sides and the slits open into said socket at the corners formed by the flat sides thereof.

7. The combination set forth in claim 1 wherein said slits are located closer to one than the

other of the buttresses between which they are located.

JOHN B. BAKER.
